UNITED STATES PATENT OFFICE.

FRANK J. COOPER, OF EMPORIA, KANSAS.

RIFLE.

1,079,471.

Specification of Letters Patent.

Patented Nov. 25, 1913.

Application filed February 25, 1913. Serial No. 750,644.

To all whom it may concern:

Be it known that I, FRANK J. COOPER, a citizen of the United States, residing at Emporia, in the county of Lyon and State of Kansas, have invented certain new and useful Improvements in Rifles, of which the following is a specification, reference being had therein to the accompanying drawing.

This invention relates to fire arms of the rifle and shot gun type and is intended to provide means whereby the shell may be thrown from the rifle when the breech block is open.

One of the objects of the invention is to provide an improved means for throwing the shell from the barrel of the rifle.

Another object of the invention is to provide an improved means for operating the shell extracting means.

Another object of the invention is to so construct the rifle that the breech block may be readily removed from the rifle and the cartridge extracting means readily removed from the barrel.

With these and other objects in view this invention consists of certain novel combinations, constructions, and arrangements of parts as will be hereinafter fully described and claimed.

In the accompanying drawings:—Figure 1 is a side elevation of the rifle with the breech block closed. Fig. 2 is a side elevation of the rifle with the breech block partially open. Fig. 3 is a side elevation of the rifle with the breech block entirely open. Fig. 4 is a fragmentary longitudinal sectional view through a rifle provided with the improved cartridge extracting means. Fig. 5 is a sectional view along the line 5—5, in Fig. 4. Fig. 6 is a fragmentary longitudinal sectional view through the barrel and breech block with the shell extracting means in the extended position. Fig. 7 is a sectional view taken through the cartridge chamber with the breech block and cartridge extracting means removed. Fig. 8 is a perspective view of the shell extracting means. Fig. 9 is a longitudinal sectional view through the inner end portion of the cartridge chamber to show the manner of holding the breech block in a closed position. Fig. 10 is a sectional view through the breech block to show the manner of mounting the plunger.

This invention is used in connection with a fire arm of the rifle and shot gun type in

which there is provided the barrel 10, stock 11, and cartridge chamber 12. The cartridge chamber 12 is provided with the usual tail 13 extending along the stock 11 and carries the hammer 14 which is operated by the usual trigger 15. Intermediate its length the chamber is provided with a cut-out portion 16 to permit the breech block which will be hereinafter described to be placed in its proper position. A pocket 17 leads from the cut-out portion 16 and an L-shaped locking pin 18 is passed through the inner end portion of the chamber and provided with an operating knob 19 engaging a spring 20. This spring normally holds the locking pin in the position shown in Fig. 9, but permits it to be moved to release the breech block. The forward portion of this cartridge chamber is provided with a longitudinally extending groove 21 and with longitudinally extending openings 22 and 23 positioned above and extending parallel to the groove 21. This groove 21 forms a track in which the cartridge extracting means travels and the slots 22 and 23 permit arms carried by the cartridge extracting means to project through the cartridge chamber so that the extracting means may be operated by the breech block. It should be noted that this groove is of approximately the same depth as the thickness of the extracting means so that when the reduced end 24 of the barrel 10 is inserted in the cartridge chamber the cartridge extracting means may travel freely in the groove.

The cartridge extracting means comprises a body portion 25 having the straight pin 26 extending from one end and having the hook shaped pin 27 extending from the opposite end and just beneath the shoulder 28 provided with the cut-out portion 29. It should be noted that this shoulder 28 is of such size that when the extractor is moved to the forward end of the groove 21 it will fit into a notch 30 formed in the inner end portion of the barrel with the cut-out portion forming a continuation of the pocket to receive the flange of a shell. It will, thus be seen that when the shell is inserted in the inner end of the barrel that the flange of the shell will be engaged by the shoulder 28 and, therefore, when the breech block is open and the extracting means moved to the rear end of the groove 21 the shell will be thrown from the gun.

The breech block 31 is of the general type

used in shot guns and is provided with a plunger 32 normally held in an extended position by a spring 33 placed about its reduced inner end portion, the outer end of 5 the plunger formed in the enlarged head 34 against which the hammer strikes. Arms 35 and 36 extend from the body portion of the breech block and are provided with openings 37 through which screws 38 may 10 be passed for pivotally connecting the breech block with the forward end portion of the cartridge chamber. The arm 36 not only serves as a means for pivotally mounting the breech block, but is provided with 15 an extension 39 having a hooked end 40 and provided with a curved shoulder forming a cam 41. The opposite edge of the extension 39 is also curved, thus forming a cam 42, the purpose for which will be hereinafter 20 brought out. When this breech block is connected with the cartridge chamber the extension 39 extends along the side of the chamber between the pins 26 and 27. When the breech block is closed as shown in Fig. 1 the 25 pin 26 will be engaged by the hook and the cartridge extractor will thus be held at the forward end of the groove 21. When the breech block is open the cam edge 42 will engage the hook shaped pin 27 as shown in 30 Fig. 2 and cause the cartridge extractor to be moved rearwardly until the shell is withdrawn from the barrel and thrown from the chamber as shown in Fig. 3. From an inspection of Fig. 3 it will be readily seen that 35 the heel 43 formed upon the hook 40 abuts against the neck 44 of the pin 27, thus preventing the breech block from being thrown forwardly to such an extent that the hook 40 would be moved out of engagement with 40 the pin 27. Upon closing the breech block the cam 41 engages the pin 26 and returns the cartridge extractor to the forward end of the groove, thus permitting the shell to be driven into the barrel by the shoulder 45 of 45 the breech block. A stem 46 extends from the breech block and is provided with an opening 47 so that when the breech block is closed and the stem passes into the pocket 50 17 the inner end of the pin 18 may pass through the opening 47, thus holding the breech block in a locked position. It is, of course, obvious that when it is desired to 55 open the breech block that the head 19 must be pressed thus moving the pin 18 out of the opening 47 and permitting the breech block to open. A device has, therefore, been provided which will prevent the shell from becoming jammed in the barrel since the extractor is operated whenever the breech 60 block is open, thereby driving the shell from the barrel and throwing it from the cartridge chamber. It should also be noted that there is no danger of the extractor not operating since the operating means for the

extractor forms a part of the breech and, 65 therefore, the breech block cannot be open without the ejector being operated.

Having thus described the invention what is claimed as new, is:—

1. In a fire arm, a cartridge chamber provided with a longitudinally extending groove, a cartridge extractor slidably mounted in said groove, pins extending from said cartridge extractor, a breech block pivotally connected with said cartridge chamber, an 70 arm extending from said breech block and positioned between the pins of said cartridge extractor, and the edges of said arm being curved to form cams for moving said cartridge extractor in said groove upon the 75 opening and closing of said breech block.

2. In a fire arm, a cartridge chamber provided with a longitudinally extending groove and with longitudinally extending slots, a cartridge extractor slidably mounted 80 in said groove, pins extending from said cartridge extractor and extending through said slots, a breech block pivotally mounted upon said cartridge chamber, and an arm provided with cam edges extending from 85 said breech block between said pins whereby the cams will engage said pins for moving said cartridge extractor upon the opening and closing of said breech block.

3. In a fire arm, a cartridge chamber provided with a longitudinally extending groove and being also provided with longitudinally extending slots positioned substantially parallel to said groove, a cartridge extractor slidably mounted in said groove, 100 said extractor comprising a body portion, a pin extending from one end of said body portion through one of the slots in said cartridge chamber, a shoulder formed upon the opposite end portion of said body portion 105 and provided with a cut-out portion to receive the flange of a shell, a pin extending from said body portion adjacent the opposite end from said first mentioned pin and extending through the remaining slot of 110 said cartridge chamber, and a breech block pivotally mounted upon said cartridge chamber and provided with an arm extending along the side of said chamber between 115 said pins whereby the opening and closing of said breech block will operate said cartridge extractor.

4. In a fire arm, a cartridge chamber, a cartridge extractor slidably connected with said cartridge chamber, pins extending from 120 said cartridge extractor, one of said pins being hook shape, a breech block pivotally connected with said cartridge chamber, an arm extending from said breech block between said pins for moving said cartridge 125 extractor upon the opening and closing of said breech block, a hook formed at the end of said arm for engaging the forward pin

to securely hold said cartridge extractor in a closed position, and a heel formed upon said hook and adapted to engage the neck of said hook shaped pin for preventing the breech block from being open to such an extent as to move said arm out of engagement with said cartridge extractor.

In testimony whereof I hereunto affix my signature in presence of two witnesses.

FRANK J. COOPER.
